CLAIM

The ornamental design for a mobile phone, as shown and described.

DESCRIPTION

1. Mobile phone

2. Mobile phone

FIG. 1.1 is a front view of a first embodiment of a mobile phone, showing my new design;

FIG. 1.2 is a back view thereof;

FIG. 1.3 is a left side view thereof;

FIG. 1.4 is a right side view thereof;

FIG. 1.5 is a top plan view thereof;

FIG. 1.6 is a bottom plan view thereof;

FIG. 1.7 is a back perspective view thereof;

FIG. 1.8 is a front perspective view thereof;

FIG. 2.1 is a front view of a second embodiment of a mobile phone, showing my new design;

FIG. 2.2 is a back view thereof;

FIG. 2.3 is a left side view thereof;

FIG. 2.4 is a right side view thereof;

FIG. 2.5 is a top plan view thereof;

FIG. 2.6 is a bottom plan view thereof;

FIG. 2.7 is a back perspective view thereof; and

FIG. 2.8 is a front perspective view thereof.

(Continued)

The broken lines show portions of mobile phone that form no part of the claimed design in the embodiments in which they are shown.

1 Claim, 12 Drawing Sheets
